DESIGN FOR A COMBINED STOVE AND GRILL OR THE LIKE

Alfred B. Frenning, Little Compton, R. I., assignor to S. M. Howes, Inc., Taunton, Mass., a corporation of Massachusetts

Application September 29, 1944, Serial No. 115,515

Term of patent 14 years

(Cl. D81—10)

To all whom it may concern:

Be it known that I, Alfred B. Frenning, a citizen of the United States of America and a resident of Little Compton, county of Newport, State of Rhode Island, have invented a new, original, and ornamental Design for a Combined Stove and Grill or the like, of which the following is a specification, reference being had to the accompanying drawing forming part thereof.

In the drawing:

Fig. 1 is a front elevational view of a combined

stove and grill or the like showing my new design;

Fig. 2 is a top plan view thereof; and

Fig. 3 is an end elevational view thereof.

The essential features of the design reside in the portions shown in full lines in the drawing.

I claim:

The ornamental design for a combined stove and grill or the like, substantially as shown and described.

ALFRED B. FRENNING.
